US00D942713S

(12) **United States Design Patent** (10) Patent No.: **US D942,713 S**
(45) Date of Patent: **** Feb. 1, 2022**

(54) **PET TOY**

(71) Applicant: **Ang Xiao**, Guangdong (CN)

(72) Inventor: **Ang Xiao**, Guangdong (CN)

(**) Term: **15 Years**

(21) Appl. No.: **29/775,922**

(22) Filed: **Mar. 26, 2021**

(51) LOC (13) Cl. **30-99**

(52) U.S. Cl.

USPC **D30/160**

(58) **Field of Classification Search**

Primary Examiner — Susan Moon Lee

(57) **CLAIM**

The ornamental design for a pet toy, as shown and described.

DESCRIPTION

FIG. 1 is a front and top perspective view of a pet toy, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another perspective view thereof, shown in an alternative position.

The broken lines in the figures illustrate portions of the pet toy that form no part of the claimed design.

1 Claim, 8 Drawing Sheets
